FUEL BURNER

William C. Skinner, Detroit, Mich.

Application April 1, 1935, Serial No. 14,171

7 Claims. (Cl. 116—30)

The invention relates to fuel burners of the type shown and described in my former Patent No. 1,225,280, issued May 8, 1917. It is the object of the present invention to simplify the construction, decrease cost of manufacture, facilitate repairs and replacement of parts, improve the operation and generally to obtain better and more efficient construction and combustion. With these objects in view the invention consists in various features of construction as hereinafter set forth.

In the drawings:

Fig. 1 is a vertical central cross section through my improved fuel burner showing the same as applied to a hot air heating furnace;

Fig. 2 is a horizontal section substantially on line 2—2, Fig. 1;

Fig. 3 is a vertical central section from front toward rear or at right angles to Fig. 1, line 3—3, Fig. 2;

Fig. 4 is a sectional perspective view;

Fig. 5 is an enlarged cross section through the fuel support on line 5—5, Fig. 2;

Fig. 6 is an elevation of the fuel support and ash dumping mechanism;

Fig. 7 is a section through the ash box showing the manner of engaging the fuel supporting member therewith;

Fig. 8 is a section showing the connection between the rockable dumper bars and the actuating mechanism therefor.

While my improved fuel burner is applicable to various heating devices, I have shown it as applied to a hot air heating furnace. The general type of structure as shown in my former patent above referred to comprises a central combustion chamber formed of refractory material and having perforated walls, a fuel holding chamber surrounding this combustion chamber, the fuel being supported upon a normally imperforate bottom, an annular air feeding chamber surrounding the fuel holding chamber and communicating therewith through apertures in the walls thereof, and a draft connection between the combustion chamber and the chimney. With such an arrangement when in full operation the volatile constituents of the fuel are distilled in the fuel chamber and commingled with air passing radially inward from the surrounding air chamber, the commingled products entering the central combustion chamber where they are burned. This central combustion chamber is also provided with an additional air supply controlled by a damper or valve and thus substantially smokeless combustion is obtained. After the volatiles have been distilled from the fuel and the solid portions have become

incandescent, the continued passage of air therethrough will produce carbon monoxide which also is burned in the combustion chamber. Thus the construction while using solid fuel becomes in effect a gas burner.

To cause the operation just described, it is essential to normally prevent entrance of air through the bottom supporting the fuel bed and at the same time it is necessary to provide for the removal of ash after the fuel is consumed. Both of these functions are very satisfactorily performed in my present fuel burner by a novel construction of dumper fuel support constituting one of my improvements. Another improved feature is in the construction of the combustion chamber which is formed in sections so that in case of the breaking or burning out of one section it can be easily replaced without dismantling the entire structure. A third improved feature is in the construction of a fire box which also is formed in sections separately removable and replaceable. These and various other improved features are the subject matter of the present invention.

In detail, and as shown in the drawings, A is a base plate on which is supported a rectangular ash box section B having an annular top plate C for supporting the walls of a circular fire box D and surrounding circular air chamber E. Supported from the plate C on opposite sides thereof and secured by bolts F are parallel angle bars G. These support a rectangular frame H which has an air sealing engagement with a depending flange C' on the plate C. The fuel support comprises a series of parallel inverted V-shaped channel bars I, some of which extend between the front and rear sides of the frame H and the central bars extend from front and rear to a rectangular central frame I' forming a support for the latter. This frame I' while externally rectangular has a circular opening therethrough which is surrounded by a circular rib I² for engaging the walls of the central combustion chamber J. A butterfly damper I³ is pivoted within the frame I', being attached to an annular plate I⁴, seated in said frame. Within the channel bars I are rocker bars K which extend from front to rear of the frame H and are journaled in bearings K' attached to said frame by bolts K². Each of these rocker bars is provided with a pair of oppositely extending wings K³ and K⁴. The wings K³ extend across the space between adjacent channel bars I, being provided with sharpened ribs K⁵ and K⁶ for engaging V-shaped grooves K⁷ on the undersides of said channel bars so as to form substantially air-tight closures therebetween. The

wings K⁴ are within the recesses in the channel bars I and are provided on their under faces with V-shaped grooves K⁸ engaged by ribs K⁹ at the outer edges of the wing K³. Thus in the closed 5 position the entire area within the frame H with the exception of that within the central frame I' is closed by the bars I and wings K³ and K⁴. The rocker bars K which extend beneath the central frame I' have the wings K³ and K⁴ interrupted 10 so as to extend only to the outside of said central frame. This central frame has its side and end walls extended downward as indicated at I⁵ to the level of the upper face of the wing K³, thus closing 15 any air connection between the space outside and inside said frame.

As previously described, the outer walls of the air chamber E are supported on the plate C and extend upward therefrom. At the top of these 20 walls is an annular plate L having a rib L' extending within the outer wall of the air chamber E and a rib L² for extending within a wall of the fire box D. This fire box is formed of a series of alternate segments D' and D² having overlapping portions D³ and D⁴ forming a break 25 joint therebetween. At their lower ends the segments D' and D² are provided with tongues D⁵ which engage a groove in the upper face of a circular rib H' integral with the frame H. The upper ends of the segments D' and D² are spaced 30 from the plate L and are provided with outwardly extending flanges D⁶ which are secured to said plate by bolts D⁷. Sleeved on these bolts are spacers D⁸ which hold the plate downward with its tongue D⁵ in engagement with the groove 35 in the rib H'. Thus all of the segments are securely held in position and together form a circular fire box. These segments are also provided with slots or apertures D⁹ through which air can 40 pass from the outer air chamber into the interior of the fuel chamber. The construction just described is such that if at any time it becomes necessary to replace any portion or portions of the fire box this can be easily accomplished by disengaging the bolts D⁷ and removing the filler blocks D⁸, after which the segments may be lifted 45 to disengage their tongues D⁵ from the groove in the ribs H' and then removed outwardly.

The wall of the central combustion chamber J is circular in horizontal section and slightly tapers 50 from its upper end downward. This wall is also formed in segments, preferably three in number, and are of a highly refractory material such as carborundum. They are further provided with slots J' which permit passage of the combustible 55 gases from the fire box into the combustion chamber where these gases are commingled with air passing upward through the opening in the frame I'. To support and hold the combustion chamber there is provided an annular frame J² which is seated in the inner portion of the plate L and which provides a ledge for engaging an outwardly extending flange J³ on each of the segments. At their lower ends the segments engage 60 the frame I' which holds them from lateral displacement. The combustion chamber is connected to the chimney draft by means of an upwardly extending tube M and a radiator N which latter is connected at its upper end by an elbow N' with the chimney flue. The arrangement is such 65 that the chimney draft will create a partial vacuum within the tube M and radiator N, this being communicated to the central combustion chamber J and causing the drawing in of the fuel gases from the fire box. The radiator N is supported from the ash pit section by means of 70

a plurality of columns N² which at their lower ends engage sockets C² on the plate C and at their upper ends engaging similar sockets on the radiator. The radiator comprises a hollow central portion N⁴ having a plurality of air tubes N⁵ 5 passing upward therethrough; also, an annular portion N⁶ extending outward from said central portion being of dished form and an upper reversely dished annular plate N⁷. Between the portions N⁶ and N⁷ are outer and inner concentric 10 walls N⁸ and N⁹ forming therebetween a flue which is connected by the elbow N' with the chimney pipe. Thus the hot gases of combustion on their way to the chimney will first pass radially outward through the central portion N⁴ and 15 around the air passages N⁵, then will pass through the annular flue between the walls N⁸ and N⁹ and finally to the chimney. This will provide a large amount of heating surface for contacting with the air enclosed within an outer air 20 jacket O.

As just described, the weight of the radiator is carried upon the columns N² while the walls of the central combustion chamber J are carried on the plates J² and L. The tube M which connects these two parts is formed in a plurality of segments which are externally engageable with the upper end of the central combustion chamber J and the lower end of the radiator and are then secured to each other by surrounding split bands 30 M' connected by bolts M². This permits of easily assembling the parts and also easily removing them in case it is necessary for repairs, it being only required that the bands M' should be removed and the segments of the tube M detached, 35 after which the segmental walls of the central combustion chamber J may be lifted out from the fire box.

Where, as shown, the fuel burner is used in a 40 hot air heating system the outer jacket O surrounds all of the other parts and permits air entering from the lower return conduits O' to come in contact with the wall of the air chamber E with the tube M and all portions of the surface of the radiator N. The upper end of the 45 jacket O instead of coning inward as is usual in hot air furnace constructions is of the reverse form, flaring outward as indicated at O². This I have found greatly stimulates circulation of the 50 heated air through the distributing conduits which latter are connected into the flaring portion as indicated at O⁴.

At the front of the jacket O is an inwardly recessed front plate P which provides access to the door Q of the ash pit and also to a door or 55 lid R for feeding fuel into the fire box. A water tank S is arranged in this front portion to humidify the air passing into the circulating system, a portion of said tank extending within said jacket.

To permit of engaging or removing the fuel 60 support, I preferably provide the following construction: The angle bars G are connected at their rear ends to the plate C by the bolts F, as previously described. These angle bars then incline downward toward the front as indicated at 65 G' to form a guideway over which the frame H may be passed and raised at its rear end. To this end the frame H has projecting pins H³ which slidably engage the angle bars G so that when said frame is moved inward through the open 70 door Q of the ash pit, its rear end will be elevated. The front end of the frame is provided with upwardly extending hooked lugs H⁴ which pass through apertures in the top plate C and are then engaged by turned buttons H⁵ to support 75

the frame in this position. When thus supported the rear bar H⁴ engages the depending flange C' on the plate C and the side bars of the frame H engage the similar depending flanges on the plate C. In this way an air seal is provided to prevent air from within the ash box passing upward through the fuel support. With the construction as described, the operation is as follows: The starting fuel is placed in the fire box and kindled through the opening normally closed by the cover R, after which this box is filled with fuel of any desired quality but preferably of lower grade, such as slack. The damper or butterfly valve I² is normally open but during the feeding of fuel into the fire box is closed by turning a handle I⁴ extending to the front of the furnace and thus the chimney draft will prevent the escape of gas outward through the fuel feed opening. After closure of the fuel door R the valve I² is open which permits air to pass upward from the ash pit section into the interior of the combustion chamber and to commingle with gaseous fuel passing inward from the fuel box into the combustion chamber. This gaseous fuel is composed of the volatiles in the solid fuel commingled with air passing through the slots in the walls of the fire box, through the fuel and slots in the walls of the combustion chamber. No air is permitted to pass upward through the fuel support as the wings K³ and K⁴ form a practically air-tight closure. However, air is permitted to enter the annular air chamber through a draft door S² and is then distributed uniformly through the slots in the walls of the circular fire box to pass radially inward through the fuel therein. When the burner is in full operation the fuel within the fire box is consumed by process of low temperature distillation, therefore, clinkers are never formed in the fire box of this furnace. All released combustible gases are drawn into the central combustion chamber where they are mixed with free oxygen admitted at the bottom or lower end of said chamber. Thus an instantaneous ignition of all combustible gases occurs, producing an intensely hot flame. The heated products of combustion pass upward through the walls of the tube and into the radiator, thus transferring said heat to the surrounding air. At suitable intervals ash may be removed from the lower part of the fire box by rocking the bars K which, as shown, may be accomplished by connecting the ends of said bars with rock arms T, all of which are pivotally connected with a shaker bar T' operated by a shaker lever T². The rocking of these bars will swing the wings K³ and K⁴ oppositely permitting the ash to drop out from the space between the stationary bars I. The wings are then returned to normal position where again an air seal is effected preventing any passage of air through the fuel support.

Some of the important features of the invention are: (1) the means for effectively preventing passage of air upward through the fuel support. This is accomplished by wings K³ and K⁴ together with the sharp edged ribs K⁵, K⁶ and K⁷ which engage the V-shaped grooves K⁸ and K⁹. There will always be a certain quantity of ash supported upon these wings which will seal any slight spaces that may remain when the wings are in closed position. At the same time the construction is such to permit of readily and effectively removing the ash as frequently as necessary.

(2) The ease with which the walls of the combustion chamber and of the fire pot may be removed is very important. There is always dan-

ger that through carelessness some portion of these walls may be broken and if the construction is such as to preclude removal of the broken part it might be necessary to disassemble the whole furnace. However, with my improved construction any section of the wall of the fire box can be removed independently from any other section by merely unfastening the bolt D¹, removing the spacer D² and then lifting the plate to disengage its tongue D³ from the groove in the rib H'. The walls of the central combustion chamber can also be removed by unclamping the bands M', disengaging the segments of the tube, after which the combustion chamber may be lifted out of engagement with the plate J².

Another important feature is that the air jacket is formed with flaring side walls O³ at its upper end while the top O⁴ inclines downward towards the center. Thus the heated air rises within the jacket and tends to pass outward into the space between these flaring walls and top, thereby stimulating circulation through the air flues O⁵.

What I claim as my invention is:

1. In a fuel burner of the type including a central perforated combustion chamber, a surrounding outer air chamber and an intermediate fuel chamber, an ash box section beneath said chambers, a top plate for said ash box section having an opening therein registering with the air chamber, fuel chamber and combustion chamber, a fuel supporting member within said ash box supported from said top plate to form an air seal therewith, said member comprising a substantially rectangular frame, a series of spaced channel bars extending across said frame and a central annular frame registering with the combustion chamber, and a series of rockable bars having overlapping oppositely extending wings, one of said wings of each rockable bar being within one of said channel bars and the other of said wings extending across the space between said channel bars and forming a sealing engagement with the opposite wing of the adjacent rockable bars whereby said channel bars and rockable bars will form in one position a closed bottom for supporting the fuel within said fuel chamber and in another position said rockable bars will permit the dumping of ash from said fuel chamber.

2. In a fuel burner of the type including a central perforated combustion chamber, a surrounding outer air chamber and an intermediate fuel chamber, an ash box section beneath said chambers, a top plate for said ash box section having an opening therein registering with the air chamber, fuel chamber and combustion chamber, a fuel supporting member within said ash box supported from said top plate to form an air seal therewith, said member comprising a substantially rectangular frame, a series of spaced channel bars extending across said frame and a central annular frame registering with the combustion chamber, and a series of rockable bars having overlapping oppositely extending wings, one of said wings of each rockable bar being within one of said channel bars and the other of said wings extending across the space between said channel bars and forming a sealing engagement with the opposite wing of the adjacent rockable bar whereby said channel bars and rockable bars will form in one position a closed bottom for supporting the fuel within said fuel chamber and in another position said rockable bars will permit the dumping of ash from said fuel chamber, a wall for said air chamber supported upon said top plate surrounding the opening therein, a wall for the fuel

chamber supported on said hollow bars and a perforated combustion chamber wall supported on said inner annular frame.

3. In a fuel burner of the type including a central perforated combustion chamber, a surrounding outer air chamber and an intermediate fuel chamber, an ash box section beneath said chambers, a top plate for said ash box section having an opening therein registering with the air chamber, fuel chamber and combustion chamber, a fuel supporting member within said ash box supported from said top plate to form an air seal therewith, said member comprising a substantially rectangular frame, a series of spaced channel bars extending across said frame and a central annular frame registering with the combustion chamber, and a series of rockable bars having overlapping oppositely extending wings, one of said wings of each rockable bar being within one of said channel bars and the other of said wings extending across the space between said channel bars and forming a sealing engagement with the opposite wing of the adjacent rockable bar whereby said channel bars and rockable bars will form in one position a closed bottom for supporting the fuel within said fuel chamber and in another position said rockable bars will permit the dumping of ash from said fuel chamber, a wall for said air chamber supported upon said top plate surrounding the opening therein, a wall for the fuel chamber supported on said channel bars and a perforated combustion chamber wall supported on said inner annular frame, said rockable bars extending beneath both the fuel chamber and the surrounding air chamber whereby any ash escaping from the fuel chamber into the air chamber will be dumped in the open position of said rockable bars.

4. In a fuel burner of the type including a central perforated combustion chamber, a surrounding outer air chamber and an intermediate fuel chamber, an ash box section beneath said chambers, a top plate for said ash box section having an opening therein registering with the air chamber, fuel chamber and combustion chamber, a fuel supporting member within said ash box supported from said top plate to form an air seal therewith, said member comprising a substantially rectangular frame, a series of spaced channel bars extending across said frame and a central annular frame registering with the combustion chamber, and a series of rockable bars having overlapping oppositely extending wings, one of said wings of each rockable bar being within one of said channel bars and the other of said wings extending across the space between said channel bars and forming a sealing engagement with the opposite wing of the adjacent rockable bar whereby said channel bars and rockable bars will form in one position a closed bottom for supporting the fuel within said fuel chamber and in another position said rockable bars will permit the dumping of ash from said fuel chamber, said sealing engagement comprising V-shaped ribs on one of said oppositely extending wings engaging V-shaped grooves in the other of said wings.

5. In a fuel burner of the type including a central perforated combustion chamber, a surrounding outer air chamber and an intermediate

fuel chamber, an ash box section having an opening beneath said air chamber, fuel chamber and combustion chamber, a normally closed fuel supporting member within said ash box section extending across said opening, an air chamber wall supported on said ash box section surrounding said opening, a top plate for said air chamber and a portion of said fuel chamber supported from said wall, a complementary annular cover plate for said fuel chamber, a circular perforated fuel chamber wall formed of a series of overlapping segments, said segments being supported at their lower ends on said member and detachably connected at their upper ends to the underside of the top plate for said air chamber whereby upon removal of said annular cover plate said segments may be individually removed and replaced without disturbance of adjacent sections.

6. In a fuel burner of the type including a central perforated combustion chamber, a surrounding outer air chamber and an intermediate fuel chamber, an ash box section having an opening beneath said air chamber, fuel chamber and combustion chamber, a normally closed fuel supporting member within said ash box section extending across said opening, an air chamber wall supported on said ash box section surrounding said opening, a top plate for said air chamber and a portion of said fuel chamber supported from said wall, a circular perforated fuel chamber wall formed of a series of overlapping segments, said segments being engaged at their lower ends with said fuel supporting member and detachably connected at their upper ends to the underside of the top plate for said air chamber whereby said segments may be individually removed and replaced without disturbance of adjacent sections, an annular cover plate for a portion of said fuel chamber removably supported from the top plate, a combustion chamber wall formed in a plurality of segments supported on said cover plate and permitting of removal without disturbance of the wall of the fuel chamber.

7. In a fuel burner of the type including a central perforated combustion chamber, a surrounding outer air chamber and an intermediate fuel chamber, an ash box section beneath said chambers, a top plate therefor having an opening therein beneath said air chamber, fuel chamber and combustion chamber, a normally closed fuel supporting member extending across said opening, an air chamber wall supported on said top plate surrounding said opening, a cover plate for said air chamber and fuel chamber supported by said air chamber wall, a fuel chamber wall formed in a plurality of overlapping segments, the lower ends of each segment having a tongue and groove engagement with said normally closed fuel supporting member and the upper ends of each segment being spaced from the cover plate of said air chamber and fuel chamber, a rib depending from said latter cover plate overlapping said segments and a spacer between each segment and the cover plate thereabove for normally maintaining the tongue and groove engagement between the lower end of said segment and said fuel supporting member whereby on the removal of said spacer each segment may be lifted to disengage said tongue and groove engagement.
